(57) **CLAIM**

The ornamental design for a holder for molten metal filters, as shown and described.

DESCRIPTION

This application may be deemed to be related to commonly owned U.S. Design patent application Ser. No. 29/334,121 filed on Mar. 20, 2009 entitled "Design For: Holder for Molten Metal Filters", the entire content of which is expressly incorporated hereinto by reference.

FIG. 1 is a rear side elevational view of a holder for molten metal filters;

FIG. 2 is a top plan view thereof;

FIG. 3 front side elevational view thereof;

FIG. 4 is a bottom plan view thereof;

FIGS. 5 and 6 are right and left side elevational views thereof, respectively; and,

FIG. 7 is a perspective view thereof.
